UNITED STATES PATENT OFFICE

159,202

AUTOMOBILE HOOD ORNAMENT

Hans W. Hahn, Chicago, Ill.

Application June 27, 1949, Serial No. 3,572

Term of patent 7 years

(CL. D14—18)

To all whom it may concern:

Be it known that I, Hans W. Hahn, a citizen of the United States, residing at Chicago, in the county of Cook and State of Illinois, have invented a new, original, and ornamental Design for an Automobile Hood Ornament, of which the following is a specification, reference being had to the accompanying drawing forming part thereof.

I claim:

The ornamental design for an automobile hood ornament, as shown.

HANS W. HAHN.
